UNITED STATES PATENT OFFICE.

CARLOS H. BOWLEN, OF HAVERHILL, MASSACHUSETTS, ASSIGNOR TO IRVING L. KEITH, OF HAVERHILL, MASSACHUSETTS.

CEMENTING MACHINE FOR SHOE-BOTTOM LININGS.

Application filed November 20, 1923. Serial No. 675,360.

To all whom it may concern:

Be it known that I, CARLOS H. BOWLEN, a citizen of the United States, a resident of Haverhill, in the county of Essex and Commonwealth of Massachusetts, have invented an Improvement in Cementing Machines for Shoe-Bottom Linings, of which the following is a specification.

This invention relates to that class of cementing machines in which a horizontally disposed grid is arranged to be moved vertically from a point within a tray containing liquid cement, and in which the grid is arranged, to be submerged to a point in which its upper, or cement carrying surface is held above the surface of the cement, so that the work to be cemented may be laid thereon and then removed and placed in position on the surface to which it is to be adhesively connected. Devices of this character have usually been employed to cement cloth or canvas backings or "doublers" for shoe uppers and also for cementing eyelet stays, and heel pads, the process usually employed being to apply the cement to the doubler stay or pad and then place it in position on the part to which it is to be connected.

In cementing sock or shoe bottom linings, in position, a different method has usually been employed, the method which has been almost universally employed having been to apply cement to the inner surface of the shoe bottom with a brush and then insert the lining and press it onto the cemented surface by hand. This method is objectionable for several reasons. It is wasteful of cement, and the person doing the work is liable to daub cement on the shoe upper lining so that additional labor is usually necessary to remove it, too much cement is often applied, so that when the shoe is placed on a form for treeing purposes, or for any other purpose, it is liable to adhere thereto, so that it is difficult to remove the shoe from the form. The hands of the worker also frequently become soiled with cement, which is transferred to the exterior or interior of the shoe, or to the top surface of the sock lining, in placing it in position. As it is often difficult or impossible to remove cement entirely from such surfaces, the additional labor expense and damage due to the application of cement to surfaces to which it is undesirable to have it applied becomes an important item of expense.

Cementing grids of the general type before referred to, for the purpose of applying cement to the bottom surface of sock linings before the lining is inserted, have not been used to any substantial extent on account of the difficulty which the operator encounters in removing the lining from the grid after it has been laid flat thereon, and particularly in doing this without soiling her fingers with cement, on account of the fact that in doing this, she usually finds it necessary to place her fingers against the edge of the lining, and when this is done it is practically impossible not to touch the cement on the adjacent grid surface.

If, however, the lining can be readily removed without soiling the fingers with the cement, it may be readily inserted in the shoe by folding it lengthwise along its middle line, inserting it in the shoe, while folded and then spreading it out flat after it has been completely inserted. In performing the work in this manner, the lining will be conveniently held in folded position while it is being inserted, by pressing the thumb and forefinger of each hand against the heel and fore parts of the lining, but, in order to do this conveniently and rapidly, it is necessary for the operator to be able to pick the lining readily from the grid, not only without soiling the finger tips, but also, by so doing, to fold it in the manner above described by the act of picking it up and to hold it in this manner during the time in which it is being inserted.

The objects of my invention are to provide a form of cementing grid in a machine of the general type above referred to on which a sock lining may be laid, so that its under surface will be suitably cemented and which is so constructed and arranged that it will so support the lining while in this position that the operator may not only readily remove the lining from the cement applying surface without having her fingers come in contact with said surface, but may fold the lining longitudinally through the middle in position for convenient insertion in the shoe without contact of the cemented surface with the inner sides of the shoe and so that the position of the fingers on the lining when removing it from said surface may be the most convenient for the inserting operation.

I accomplish these objects by providing a grid having a cement applying surface adapted to coat the bottom surface of the lining with cement to a sufficient extent to cause the necessary adhesion when laid thereon and which is arranged to support the middle portion longitudinally at a higher elevation than the side portions, so that the side portions of the lining may be pinched together and the lining lifted from the grid in position for ready insertion in a shoe.

For a more complete understanding of my invention reference is made to the accompanying drawing in which:

Fig. 1 is a plan view showing a preferred embodiment of my invention.

Fig. 2 is a transverse sectional view thereof on a larger scale.

Figs. 3 and 4 are detail views illustrating the method of removing the lining from the cementing grid.

Figs. 5 and 6 are sectional views illustrating the manner of inserting the lining after removal from the grid and

Figs. 7 and 8 are plan and end views illustrating a modified embodiment of my invention.

According to my invention, I provide a grid frame which comprises side rods *a* which are supported in end bars *b* at each end, said end bars being attached to vertically disposed lifting rods *c* which are adapted and arranged to be moved vertically by a treadle or other suitable means not shown, so that the grid may be raised and lowered in a liquid cement containing pan or tray *d*, from a position in which it is completely submerged to a position in which its upper side is above the liquid level. A series of bars *e*, consisting of strips of flat metal are arranged edgewise, or in vertical planes and in parallel relation on said rods *a*, which pass through the opposite end portions of said bars, and on which said bars are held in spaced relation by means of interposed washers *f*, said bars and washers being clamped together by nuts on the ends of the rods *a*, in a well known manner.

The upper edges of said bars are finished to form cement carrying faces arranged in alignment transversely and are convexly curved longitudinally on the same radius, so that they lie in a cylindrical surface having a horizontal axis and form a transversely convex cementing surface. The grid is of oblong form, the length which corresponds to the combined thickness of the bars and interposed washers, being substantially greater than the width, which corresponds to the length of the bars, so that the cement applying surface of the grid is transversely convex and longitudinally horizontal, the highest points on said surface being in the

middle longitudinal line thereof. The length of the cementing surface thus provided is made somewhat longer than the length of the longest sock lining which is likely to be cemented thereon and, preferably, at least, twice the width of such lining.

In using the device, the grid is submerged in the liquid cement and then lifted, so that the upper edges of the bars are exposed. The operator then, while the grid is thus held, lays a sole shaped sock lining, as *x*, on the surface formed by said edges in longitudinal position, so that a longitudinal element of said surface will approximately coincide with the middle longitudinal line of the lining, as indicated in Fig. 1. As the linings are usually made of very thin flexible leather, it will conform by its own weight to the cementing surface, so that, as soon as the lining is placed thereon, a series of transverse stripes of cement will be applied to the under surface of the lining throughout its length which will extend from one side edge to the other. It will be observed that when the lining is laid on the grid in this manner, its middle portion will be held above its side portions, so that it will be partly folded longitudinally, as indicated in Figs. 2 and 3.

The operator then places the thumb and forefinger of each hand on the wider portion of the heel and forepart of the lining, as indicated in Fig. 3, and then, while pressing firmly downward, moves the thumb and finger of each hand toward each other, so as to bring the opposite side portions of the lining together, as indicated in Fig. 4, thus folding the lining longitudinally throughout its entire length and bringing the opposite portions of the cemented surface together. As thus held, but little or none of the cemented surface will be exposed, so that the operator may then insert the lining in the shoe while held in this position, and without changing the position of her hands thereon, in the manner indicated in Fig. 5. The lining usually has enough inherent stiffness, when held in this manner, to prevent it from bending down at points at which it is not supported, so that it may be readily inserted in the shoe. When it has been fully inserted, it will be spread out flat on the shoe bottom, so that it will adhere thereto. In this way the lining may be readily inserted without having the cemented surface come in contact with the lining of the shoe upper. By providing a form of grid which performs a preliminary folding of the lining at the same time that it cements it, the operator is able to finish the folding operation by the act of removal of the lining from the grid and do this quickly without difficulty and without contact of the fingers with the cement carrying surface of the grid, this latter fact being a matter of great import-

tance, when the operation is repeatedly performed.

While the operator may ordinarily place the lining on the middle portion of the grid, as shown in Fig. 1, this is not essential, provided it is placed thereon in longitudinal relation, and it is easily possible for two operators to work on one machine at the same time by working at opposite sides of the grid, and placing the linings thereon at each side of its middle line, the curvature of the cement applying edge of each bar being the same throughout its length. The quantity of cement applied to the lining is sufficient and sufficiently well distributed to hold the same securely in position when applied in the manner hereinbefore described.

In Figs. 7 and 8, I have shown a modified form of my invention, which, while advantageous, has not in practice been found to be as advantageous as the form already described.

In this form the manner of supporting the grid bars *g* thereof is the same as that already described, but the bars are bent in zig-zag formation, so that the extreme lateral positions at one side of one bar will be opposite the extreme lateral position of the corresponding adjacent points at the adjacent side of the next bar. The edges at the opposite side of the transverse middle line of each bar is formed to slope downward in an inclined plane from this point, as shown in Fig. 8, so that the cementing surface which is formed by the upper edges of the bars lies in two planes which meet in the middle longitudinal line of the grid.

The manner of using this form of grid is practically identical to that already described, with the exception that care must be taken so to place the lining thereon that its middle line approximately coincides with the vertex of the angle or the line of intersection of the planes in which the cementing surfaces lie. While with this form of my invention, the operation of preliminary partial folding will be more effectively performed by the grid than it will be with the convex construction already described, so that the lining may be folded more easily and accurately, as it is a prerequisite that the lining be placed accurately in position on the grid, it has been found that the operator cannot do the work as rapidly as with the convex form of grid as time is lost in placing it in position. Also, except where extremely thin linings are being cemented, it is necessary to draw the fingers along the length of the lining and press it down firmly on the grid to insure contact with the bars at all points, and this causes further delay, and with the convex grid, all portions of the lining will be cemented by placing it in position thereon. The zig-zag construction is advantageous when it is especially desired

to spread the cement over practically the entire surface and not have it applied in stripes, as the movement of the opposite portions of the lining on the grid surface transversely, or longitudinally of the bars will cause a movement obliquely to the portions of the bars engaged. It will be obvious that the zig-zag construction may be applied with equal advantage to the bars having the convex edge shown in Fig. 2, but an objection to this construction is that it increases the frictional engagement on the lining when the opposite sides of the latter are pinched together while pressed onto the grid. That is, the straight bars offer much less resistance to the action of sliding the opposite portions together on the grid, than the zig-zag construction.

The relative angular positions shown of the opposite side portions of the faces, while the most desirable of which I am aware, may be somewhat varied without departing from the spirit of my invention.

I claim:

1. A machine for cementing shoe bottom linings comprising a horizontally disposed, vertically movable grid, composed of a series of suitably spaced transversely extending bars having cement carrying faces on their upper edges arranged in transverse alignment and sloping uniformly from the middle to each end thereof, to provide a longitudinally horizontal cementing surface having oppositely declining side portions, for partially folding the lining longitudinally as its under surface is cemented.

2. In a machine for cementing shoe bottom linings, a horizontally disposed, vertically movable grid having a series of transversely extending bars spaced apart to permit the flow of liquid cement therebetween, said bars having transversely aligned and longitudinally convex faces to form a longitudinally horizontal and transversely convex cement applying surface the highest points of which are in the middle longitudinal line thereof, said surface being arranged to support the longitudinal middle portion of the lining above its side portion and partially fold the same longitudinally.

3. A machine for cementing shoe bottom linings comprising a horizontally disposed, vertically movable grid of oblong form and composed of a series of suitably spaced transverse bars having cement carrying faces on their upper edges, said faces being convexly curved longitudinally of the bars and arranged in transverse alignment to provide a cylindrically shaped cementing surface adapted to support the middle portion of the lining above its side portions when placed thereon in longitudinal relation, partly to fold the same longitudinally at the time it is cemented.

4. A machine for cementing shoe bottom

- linings comprising a horizontally disposed, vertically movable grid composed of a series of transverse bars arranged in parallelism and having longitudinally convex cement carrying faces on their upper edges, disposed in a cylindrical surface to support the lining in a position in which it is partly folded longitudinally as the cement is applied to its under surface.
- 10 5. In a machine for cementing shoe bottom linings a horizontally disposed, vertically movable grid arranged to be submerged in liquid cement and to be elevated above the

level thereof, said grid comprising a series of spaced, parallel bars having faces on their upper edges arranged in horizontal transverse alignment and longitudinally curved about a horizontal axis disposed beneath the middle thereof to provide a cementing surface arranged to support the longitudinal middle portion of the lining above the level of its side portions and partly fold the same longitudinally.

In testimony whereof, I have signed my name to this specification.

CARLOS H. BOWLEN.
